UNITED STATES PATENT OFFICE.

HAROLD ROWNTREE, OF CHICAGO, ILLINOIS, ASSIGNOR TO NATIONAL PNEUMATIC COMPANY, OF CHICAGO, ILLINOIS, A CORPORATION OF WEST VIRGINIA.

OPERATING MECHANISM FOR ELEVATOR-HATCHWAY DOORS.

1,172,562.

Specification of Letters Patent.

Patented Feb. 22, 1916.

Application filed March 8, 1912. Serial No. 682,525.

To all whom it may concern:

Be it known that I, HAROLD ROWNTREE, a citizen of the United States, residing at Chicago, county of Cook, and State of Illinois, have made a certain new and useful Invention in Operating Mechanism for Elevator-Hatchway Doors, of which the following is a specification.

This invention relates to operating mechanism for elevator hatchway doors.

The object of the invention is to provide a folding door arrangement for elevator hatchways and mechanism for operating the doors into folded or open position or into 15 distended or closed position.

A further object of the invention is to provide a construction of elevator hatchway door operating mechanism which is simple, efficient and capable of being easily and 20 readily controlled.

Other objects of the invention will appear more fully hereinafter.

The invention consists substantially in the construction, combination, location and relative arrangements of parts, all as will be 25 more fully hereinafter set forth, as shown in the accompanying drawing, and finally pointed out in the appended claims.

Referring to the accompanying drawing, 30 and to the various views and reference signs appearing thereon, Figure 1 is a view in front elevation, parts broken out, showing a construction of elevator hatchway door and operating mechanism therefor embodying the principles of my invention, the door panels being actuated by motor mechanism. Fig. 2 is a view similar to Fig. 1, showing 35 manually operated mechanism for moving the doors. Fig. 3 is a view in vertical section on the line 3, 3, Fig. 1, looking in the direction of the arrows.

The same part is designated by the same reference sign wherever it occurs throughout the several views.

45 In the construction of elevator hatchways, it is desirable to provide as wide a door opening therein as practical. Where sliding or swinging doors are employed a large part of the available space in front of the 50 elevator hatchway which would otherwise be available as an entry way or passage through the doorway of the hatchway, into or out of the elevator car, is very materially occupied by the portions or sections of the 55 door.

In accordance with the principles of my invention, I propose to employ doors composed of foldable sections or panels hinged together and suitably pivoted within the doorway of the hatch, and preferably at opposite sides of the doorway. I also provide means for operating the door panels or sections so as to fold the same upon each other, in opening and to distend the same into line with each other to close the same.

60 In accordance with the broad principles of my invention, I propose to employ means for operating the door panels or sections in unison. That is to say, in carrying out my invention, and in the particular embodiment thereof shown in the drawing, I employ for each doorway of the hatch, two door sections, each door section comprising two panels hinged together at their proximate edges, the outer panel of each section 65 being mounted or carried upon ball bearing or other form of hinges or pintles, whereby the door sections may be rocked or swung, the outermost panel of each door section carried upon ball bearing or other form of 70 pivot pintles at its upper and lower outer corners respectively. Upon these pivot pintles this outer panel of the door section will 75 swing or rock into and out of open position. Each of the inner panels is hinged to the 80 inner edge of the co-operating outer panel.

While I have shown the door sections composed of only two hinged panels, it is to be understood that my invention, as defined in the claims, is not to be limited or restricted in this respect.

85 In accordance with the principles of my invention, I propose to provide connections whereby the two outermost panels of the door sections are simultaneously rocked or 90 swung in opposite directions. The intermediate connections for securing the simultaneous movement of the outermost door panels of the door sections, is preferably located within a channel or chamber above 95 the doors. The operating mechanisms or connections may be controlled and operated either manually or by power devices. In Fig. 1, I have shown power mechanism for this purpose, whereas in Fig. 2, I have shown 100 manually operated devices for accomplishing the operation and actuation of the doors. Whether manual devices or power devices are employed for operating the door panels 105 or sections, the control of such connections 110

and mechanism may be effected in any suitable or convenient manner and preferably from a point adjacent the door sections or panels. Suitable control handles may be employed for this purpose.

- 5 Referring to the drawings, and particularly to Fig. 1, I have shown the door as composed of two sections, each comprising the panels A, B. The panel B constitutes 10 the outermost panel of each door section, and each outermost panel B, carries ball bearings or other form of pivot pintles C, D, respectively at its upper and lower outermost corners and in vertical line with each 15 other. The pintle D, comprises a point or projection carried by plate E secured to the lower outer corner of the panel and is fitted into a seat or socket suitably let into or formed in the floor of the hatch doorway. 20 The upper pintle or pivot C, is in the form of a pointed screw adjustably mounted and locked in a convenient fixed part F, attached to or carried by the frame work above the doorway, the point of the screw 25 being fitted or received in a seat formed in a bracket G, H, carried by the uppermost outer corner of the door panel B. This arrangement affords a most convenient construction for assembling and erecting the 30 door panels or door sections. The casting G, H, may be conveniently, easily and economically made and applied by bolting or otherwise securing it to the uppermost corner of the door panel B. 35 Each of the castings G, H, at its upper end, is provided with an arm K, in the nature of a crank arm. To these crank arms K are connected rods L, M, the actuation of which effects the rocking of the panels B 40 about its pintles. The rods L, M, extend from the outermost corners of the opposite door panels B, toward each other, and at their proximate ends are connected to opposite ends of a lever N, which is pivoted intermediate its ends as at O. By rocking the 45 lever N, the two rods L, M, are simultaneously projected in opposite directions with reference to each other. The rod L, connected to the crank arm K, of casting H, rocks the left 50 hand door panel B, while the rod M, projected in the opposite direction, rocks the crank arm K, of the casting G thereby rocking the right hand panel B, of the door section on the opposite side of the doorway. 55 As above indicated either power mechanism or manually operated mechanism may be employed for operating the doors. That is to say, either motor or manual connection 60 may be employed for rocking the lever N. In Fig. 1 power mechanism is shown for this purpose. The power mechanism in this instance comprises the two differentially sized cylinders P, Q, having a common piston rod R carrying a cross head S. This cross 65 head S, is connected to the lever N, to rock

the same when the piston rod R is shifted in one direction or the other. A conveniently arranged valve mechanism indicated at T, may be employed for controlling the supply and exhaust of the operating medium to and 70 from the power cylinder. The valve mechanism may be operated or controlled in any suitable or convenient manner. A simple arrangement is shown wherein a rod A', is connected to the valve mechanism and to 75 this rod A', is connected one arm of a bell crank lever B'. This bell crank lever constitutes a control lever and is located in convenient position to be operated by the elevator attendant when the elevator car arrives at or opposite the landing at which the door mechanism is located and is to be operated.

The operation is very simple. When an elevator car arrives opposite a landing the 85 elevator attendant manipulates the bell crank control lever B', thereby actuating the valve mechanism T, through the rod A'. This controls the supply and exhaust 90 of operating medium to the motor mechanism, thereby causing the piston rod R, to be shifted in one direction or the other, consequently rocking lever N. As shown in Fig. 1, the lever N, is in the position which it occupies when the door panels are distended 95 into line with each other, that is for instance, with the doors closed. Now, by manipulating the control handle B', to supply operating medium to the motor, the lever N is rocked so as to move the rods L, M, 100 outwardly or away from each other. This movement of the rods L, M, causes the castings G, H, to be rocked through the connection of said rods with the crank arms K, thereby rocking the outer panels B, B, of 105 the door sections outwardly or in a direction to open the door. This movement of the outer panels B, B, causes the inner panels A, to fold upon the outer panels B. At the upper inner corners of the panel A, 110 are provided suitable guide devices indicated at D', Fig. 1. These are in the form of rollers, or other engaging devices, secured to the uppermost inner corners of the panels A and which engage within a track or way formed by the plates E'. (See Fig. 3.) This arrangement affords an efficient 115 guide for the inner edges of the panels A, during the swinging movement of the panels B, thereby causing the panels A to be moved 120 into collapsed relation upon or in folded position upon the outer panels B, thereby opening the doorway. A reverse movement of the control lever B', causes the panels B to be rocked or swung simultaneously in the opposite direction thereby causing the panels A, to correspondingly move into opposite direction so as to become distended 125 into line with the outer panels B to close 130 the doorways.

Referring now to Fig. 2 the lever N' , pivoted intermediate its ends at O' , is connected at its ends to the respective proximate ends of rods L' , M' , the outer ends of 5 said rods being connected, respectively, to the crank arms, K' , of the castings G , H . Also connected to the lever N' , is a rod F' , which, at its other end, is connected to one arm of a bell crank lever G' , to the other 10 arm of which is connected one end of a swinging rod T' , the end of said swinging rod being pivotally connected to an arm T' , of a control lever R' , said control lever being pivotally mounted intermediate its 15 ends as indicated at F' . By suitably rocking the control lever R' it will be observed that the lever N' , is manually actuated to rock or swing the door panels B , A , into open and closed positions, thereby effecting 20 the manual operation of the doors. If desired, and in order to afford means for locking the door panels in their open or closed position, I employ a bent portion, indicated at A^2 , in rod T' adapted to permit said rod 25 to pass beyond the dead center relation thereof when the lever R' , is rocked or swung, as will be readily understood, thus affording a convenient lock to retain the door sections closed or opened, as the case 30 may be. In other respects the construction and arrangement shown in Fig. 2, and the mode of operation thereof, remains the same as above described with reference to the 35 construction and arrangement shown in Fig. 1.

In practice I prefer to employ a hatchway inclosure frame work comprising side posts B^2 , C^2 , respectively arranged on opposite sides of the doorway where the doors, 40 sections or panels A , B , are to be employed. A convenient arrangement is shown wherein these vertical side posts of the framing are in the form of sheet metal stamped out and suitably ornamented, to form channel 45 posts or members. The operating rod A' , for instance, (Fig. 1 or E' , Fig. 2) together with the control levers T' , R' , being located within the channels or chambers of said side posts. Similarly I propose to employ 50 a panel member D^2 , of sheet metal, and to arrange the same transversely across the space between the side posts B^2 , C^2 , over or above the doorway. Within the channel or chamber of this horizontal member D^2 , 55 I propose to locate the operating levers, N , N' , and the connections L , L' , M , M' , for operating the doors or door panels. In case of the power operated mechanism I also propose to locate the motor mechanism 60 within this channel. If desired, a cover hinged or otherwise connected to the hatchway framing and indicated at E^2 , may be employed for inclosing the mechanisms or connections within the chamber of panel D^2 . 65 In practice I prefer to arrange the inner

surfaces of the door panels, when closed, to be in vertical line with the paneling or framing above and below the doorway, and with the inner edge or surface of the floor members, or beams, both above and below 70 the doorway, as clearly indicated in Fig. 3, thus affording a flush surface presented toward the path of travel of the elevator car.

Having now set forth the object and nature of my invention, and various constructions embodying the principles thereof, what I claim as new and useful, and of my own invention, and desire to secure by Letters Patent of the United States, is,—

1. An elevator hatchway frame having 80 a doorway, in combination with a door composed of panels hinged together, at their meeting edges, a pivot pintle carried by the outer panel at its lower outer corner, a casting carried by said outer panel at its upper outer corner, a pivot screw engaging said casting in vertical line with the lower pivot pintle, means for rocking said panel about its pivots, and means for guiding the hinged panel. 85

2. An elevator hatchway frame having 90 a doorway, in combination with a door composed of panels hinged together, a pivot pintle carried by the outer panel at its lower outer corner, a pivot seat for said pintle, a 95 casting carried by said outer panel at its upper outer corner, said casting having a crank arm, a pivot screw arranged in vertical line with the pintle and engaging said casting, means engaging said crank arm for 100 rocking said panel about its pintle axes, and means for guiding the hinged panel.

3. An elevator hatchway having a doorway, a door therefor comprising panels arranged at opposite sides thereof, said panels 105 having pivot pintles at their lower outermost corners, castings connected to the upper outermost corners of said panels, pivot screws in vertical line with the pivot pintles and engaging said castings, said castings 110 having crank arms, connections intermediate said crank arms, whereby said outer panels rock or swing together, and additional panels hinged to said pivoted panels, and means for guiding said hinged panels. 115

4. An elevator hatchway frame having a doorway, a panel arranged above the doorway in the frame and forming a chamber, a door for the doorway, comprising panels arranged at opposite sides thereof, said 120 panels having pivot pintles at their lower outer corners, pivot seats for said pintles, castings secured to the upper outer corners of said panels, pivot screws arranged in vertical line with said pintles and engaging 125 said castings, crank arms connected to or carried by said castings, a lever arranged within said chamber, rods connecting the ends of said lever to said crank arms at opposite sides thereof, means for rocking said 130

lever, additional panels hinged to the pivoted panels, and means for guiding said hinged panels.

5. An elevator hatchway frame having a doorway, posts arranged on opposite sides of said doorway, a panel arranged above said doorway, to form a chamber, a door for the doorway comprising panels arranged at opposite sides thereof, said panels having pivot pintles at their lower outermost corners, pivot seats for said pintles, castings connected to the uppermost outer corners of said panels, pivot screws arranged in vertical line with said pintles and engaging 10 seats in said castings, said castings having crank arms presented in opposite directions with reference to each other, a pivoted lever arranged within said chamber, rods connecting the ends of said levers to said crank arms respectively, whereby said crank arms and their connected or associated door panels are simultaneously rocked or moved in opposite directions when said lever is rocked, means connected to said lever for 15 rocking the same, and means arranged within a side post of the frame for controlling 20 the operation of said lever.

6. An elevator hatchway frame having a doorway, side posts arranged on opposite sides of said doorway, a panel arranged above said doorway and forming a chamber, a door for the doorway comprising panels arranged at opposite sides thereof, said panels having pivot pintles at the lower 25 outermost corners thereof, pivot seats for said pintles, castings carried by the uppermost outer corners of said panels, pivot screws arranged in vertical line with said pintles and engaging seats in said castings, 30 crank arms carried by said castings and respectively presenting in opposite directions 35 40

with reference to each other, a motor arranged within said chamber and connected to said crank arms, and means for controlling said motor, whereby said door panels 45 are rocked or swung in opposite directions simultaneously, additional panels hinged to said pivoted panels, and means for guiding said hinged panels.

7. An elevator hatchway frame having a doorway, posts arranged on opposite sides thereof, a panel arranged above the doorway to form a chamber, a door for the doorway comprising panels arranged at opposite sides thereof, said panels having pivot 50 pintles at their lower outermost corners, pivot seats for said pintles, a casting connected to the upper outermost corner of each of said panels, pivot screws arranged in vertical line with said pintles and engaging 55 seats in said castings, crank arms carried by said castings, and presenting in opposite directions with respect to each other, a power motor located within said chamber and connected to said crank arms, whereby 60 when said motor is operated said panels are rocked or swung simultaneously in opposite directions, means for controlling said motor, said means located within a side post 65 of the doorway, additional panels hinged to 70 said pivoted panels, and means for guiding said additional panels.

In testimony whereof I have hereunto set my hand in the presence of the subscribing witnesses, on this 20 day of February A. D., 75 1912.

HAROLD ROWNTREE.
